SPRAYER ATTACHMENT FOR POWER LAWN MOWERS OR THE LIKE

Earl H. Weller, Bay Village, Ohio, assignor to
Leonard M. Strunk, Coatesville, Pa.

Application May 13, 1954, Serial No. 30,450

Term of patent 14 years

(Cl. D14—3)

Fig. 2.

Fig. 1

Figure 1 is a front perspective view of a sprayer attachment for power lawn mowers or the like showing my new design; and

Figure 2 is a rear perspective view thereof.

The lawn mower shown in Figure 1 by means of phantom lines is disclosed only for the purpose of illustration.

I claim:

The ornamental design for a sprayer attachment for power lawn mowers or the like, as shown and described.
